Spencer, Hardman & Fehr ATTORNEY

UNITED STATES PATENT OFFICE

JOHN B. BREEN, OF DAYTON, OHIO, ASSIGNOR TO FRIGIDAIRE CORPORATION, OF DAYTON, OHIO, A CORPORATION OF DELAWARE

REFRIGERATING APPARATUS

Application filed September 27, 1929. Serial No. 395,587.

This invention relates to refrigerating apparatus and especially to a type of refrigerating apparatus commonly referred to as a display case.

5 An object of the invention is to provide a display case having a maximum of storage and display space for bulky food stuff such as butter and cheese with a very economical but sufficient cooling means for the same.

10 Another object of the invention is to provide a mechanical cooling unit with valves inside a display case having provision for very easy access to the valves from the exterior of the casing.

15 Further objects and advantages of the present invention will be apparent from the following description, reference being had to the accompanying drawing, wherein a preferred form of the present invention is clearly shown. In the drawing:

Fig. 1 is a cross section through a preferred form of the invention as applied to a display case;

Fig. 2 is a cross section on line 2—2 of Fig.

25 1, and

Fig. 3 is a rear view of the refrigerator cabinet in Figs. 1 and 2.

One of the problems in stores wherein space is at a premium is the adequate storage and display of bulky food stuffs such as tub butter and cheese. These manufactured dairy products do not need the low temperature that other foods such as fish and meat require. Therefore, their preservation in a state desirable for display and selling is a certain range of temperature such as that between 55 and 60° F. which is very desirable if not essential for their preservation in a suitable condition until sold. Accordingly it is one of the objects of this invention to provide a refrigerated storage space for the bulky tub butter and cheese in which a very economical cooling means is located which will supply the necessary refrigeration required.

It is also an object of this invention to provide means whereby the valves controlling the inlet and outlet of a refrigerant to or from this cooling means may be readily ac-

cessible from the exterior of the display case. By this ready accessible means, if it is necessary to shut off the refrigerant lines in order to move the case from one place in the store to another, or for any other reason, this shutting off can be quickly and easily accomplished as will be more fully described later.

In the drawing is disclosed a preferred form of refrigerator display and storage case embodying the invention. A base 10 and lower walls 11 enclose preferably a storage compartment 12 insulated by means of an insulation 13 such as slabs of rock cork. This storage portion of compartment 12 has an inner lining 14 which of course is of a material such as porcelain coated steel which is easily cleaned. The portion of the walls from the inner side of the outer covering to the outer side of the inner lining are suitably sealed with a bituminous cement such as 45 hydrolene. Suitable insulated doors 15 swingingly hinged in a framework 16 provide ready access to the storage portion of the cabinet.

50 In the upper part of the cabinet is the display portion or compartment 17. This display portion is surrounded by suitable insulation whenever practical and has transparent portions in the front and rear walls of the casing. As disclosed in the drawing the front and rear walls are preferably sloping from the insulated top portion 19. The front wall preferably has a large panel of glass 20 suitably sealed in a framework 21. The rear wall has a plurality of sliding doors 22 having glass panels 23 suitably sealed in the same. The sloping rear wall preferably branches into a horizontal portion 24 available as a counter or shelf for the convenience 55 of the clerk waiting on customers.

55 A partition 25 separates the storage compartment 12 from the display compartment 17. This partition preferably has a fairly large opening 26 at the rear center edge. A 60 cooling unit is located in this opening 26 and has portions extending into the display portion 17 and the storage portion 12 of the cabinet. This cooling unit is preferably composed of a single boiler or tank 27 and has 65

depending ducts 28 extending through the opening 26 into the storage compartment 12. This boiler and ducts are preferably of the flooded float control type such as disclosed in the patent to R. G. Osborn, 1,556,708, issued October 13, 1925. If desired, suitable fins 29 may be attached to these ducts 28 to increase the refrigeration.

A suitable inlet valve 30 and outlet valve 31 for the refrigerant in the boiler 27 are located on the one end of this boiler. In case the refrigerant lines have to be shut off for removal of the show case from one part of the store to another or in case examination or repairs are necessary, these valves are made very accessible for such shutting off of the refrigerant. This is accomplished by having an easily removable door 32 in the rear wall adjacent the valves on the cooling unit 27. This insulated door 32 is preferably attached to the rear wall by any suitable fastening means such as the screws 33.

One or more openings 34 are provided in the front part of the partition 25 for the air circulation to pass from the storage compartment 12 to the display compartment 17. This opening 34 may extend for the major portion of the length of the cabinet. An up-standing projection 35 prevents the hole 34 from being closed by food stuffs.

If desired, the refrigerant liquefying unit, which is preferably of the compressor-condenser-receiver type such as disclosed in the patent to R. G. Osborn above referred to, may be located in the storage compartment 12 or may be located in the basement or other out-of-the-way portion of the store. As the temperature in this cabinet has generally a different range than other refrigerators, such as meat counters, etc. in the store, one large refrigerant liquefying unit could be used to supply liquid refrigerant to the various show cases in conjunction with a two-temperature valve such as disclosed in the patent to H. W. Wolverton, 1,699,576, issued January 22, 1929.

It will be noted that the cabinet disclosed has a large truncated cone display portion especially suitable for tub size butter and cheese. Of course, small packages of butter and cheese could be placed about these dairy products of larger bulk. A lower compartment 12 also has the adequate storage space for these large bulky objects or for a large quantity of small package goods. In spite of this large display case, one cooling unit is provided to adequately cool the entire cabinet.

The warm air descends over the cool surface of the tank 27, ducts 28, fins 29 and heat in the air is absorbed by these elements and directed to the liquid refrigerant in the interior of the cooling unit. Cold air passes through the storage compartment 12 and up through one or more openings 34 in the front

part of the partition 25 to the display portion 17 of the cabinet. After absorbing any undesirable heat from the articles in the display portion of the cabinet, the air is again cooled by the cooling unit in passing through the opening 26.

While the form of embodiment as herein disclosed constitutes a preferred form, it is to be understood that other forms might be adopted, all coming within the scope of the claims which follow.

What is claimed is as follows:

1. A mechanically cooled refrigerator cabinet having an upper display compartment and a lower storage compartment, and a partition wall separating said compartments, said wall having an opening provided therein, a compact, block-like cooling unit removably supported and disposed in said opening and having a portion extending above said partition wall into said display compartment and another portion extending below said partition wall into said storage compartment, said opening being larger than the cooling unit, said cooling unit being adapted for installation as a unit.

2. A mechanically cooled refrigerator cabinet having an upper display compartment and a lower storage compartment, and a partition wall separating said compartments, said wall having an opening provided therein, a flooded cooling unit removably supported and disposed in said opening and having a portion extending into one of said compartments, said opening being larger than the cooling unit, said flooded cooling unit being adapted for installation and removal as a unit.

3. A mechanically cooled refrigerator cabinet having an upper display compartment and a lower storage compartment, a partition wall separating said compartments, said wall having openings therein, a flooded unitary cooling unit including a tank removably supported in said display compartment above one of the openings in said partition wall and having ducts attached thereto extending through said last mentioned opening into said storage compartment, said opening being larger than the cooling unit, said flooded cooling unit being adapted for installation and removal as a unit.

4. A mechanically cooled refrigerator cabinet having an upper display compartment and a lower storage compartment, an insulated partition wall separating said compartments, said wall having openings therein, a cooling tank supported in said display compartment above one of the openings in said partition wall and having ducts attached thereto extending through said last mentioned opening into said storage compartment, valves for controlling the flow of refrigerant to and from said tank, said valves being carried by said tank, said cabinet

being provided with an opening leading from the exterior of the cabinet to said last mentioned opening, and readily removable closure means for said opening in the cabinet.

5. A mechanically cooled refrigerator cabinet having an upper display compartment and a lower storage compartment, a partition wall separating said compartments, said partition wall having openings adjacent the front and rear portions of the cabinet, and a unitary cooling unit removably supported and disposed within one of said openings, having a portion extending above said partition wall into said display compartment and another portion below said partition wall into said storage compartment, said opening being larger than the cooling unit, said cooling unit being adapted for installation and removal as a unit.

15 20 In testimony whereof I hereto affix my signature.

JOHN B. BREEN.
